JOHN W. KROEZE, OF BURLINGAME, CALIFORNIA.

SANDING-MACHINE.

1,134,085.

Specification of Letters Patent. Patented Mar. 30, 1915.

Application filed November 15, 1913. Serial No. 801,203.

To all whom it may concern:

Be it known that I, JOHN W. KROEZE, a citizen of the United States, residing at Burlingame, in the county of San Mateo and State of California, have invented new and useful Improvements in Sanding-Machines, of which the following is a specification.

This invention relates to a machine for sanding panels and other flat surfaces, and particularly pertains to a mechanism for conveying a panel to and from a sanding belt.

It is the object of this invention to provide a mechanism by which a panel of considerable width can be automatically fed to a comparatively narrow sanding belt so as to effect a uniform sanding throughout the surface of a panel.

Another object is to provide means in an apparatus of the above character for normally controlling the panel moving mechanism so as to vary the extent of the sanding of the panel at portions of the surface thereof where such operation may be necessary in order to obtain a proper finish.

A further object is to provide means in an automatic panel sanding machine having a movable panel-carrying table adapted to travel longitudinally of a sanding belt and transverse thereto, by which the length or distance of travel of said table in either direction may be varied as occasion may require to suit the size of the panel to be sanded.

A further object of the invention is to provide an automatic sanding machine which is simple in construction and efficient and reliable in operation.

Further objects will appear hereinafter.

The invention primarily resides in a movable frame mounted to travel in transverse relation to a continuous sanding belt, a panel-carrying table movable on said frame longitudinally of the belt, power operated means for moving said frame and table from one source of power in either direction collectively or separately and independent of each other, and means for automatically reversing the direction of travel of the frame and the table at variable predetermined points.

The invention further consists of the parts and the construction and combination of parts as hereinafter more fully de-

scribed and claimed, having reference to the accompanying drawings, in which—

Figure 1 is a plan view of the invention with parts broken away. Fig. 2 is a front elevation of the machine. Fig. 3 is a vertical longitudinal section on the line *b*—*b* of Fig. 4. Fig. 4 is a cross section on the line *c*—*c* of Fig. 3. Fig. 5 is a detail plan view of one of the adjustable bumpers. Fig. 6 is a detail in section of the belt shoe shifting mechanism. Fig. 7 is a detail of a carriage shifting device. Fig. 8 is a detail plan view of the frame and table shifting mechanism. Fig. 9 is a detail in side elevation of same. Fig. 10 is a detail vertical section on the line *f*—*f* of Fig. 9. Fig. 11 is a detail vertical section on the line *g*—*g* of Fig. 8. Fig. 12 is a detail vertical section on the line *h*—*h* of Fig. 9. Fig. 13 is a detail vertical transverse section on the line *i*—*i* of Fig. 8. Fig. 14 is a detail in side elevation of one of the adjustable stops.

In the drawings A—A' represents a pair of separated frame members which may be of any suitable character and construction. 80 Rotatably mounted on each of the frame members A—A' is a pulley wheel 2—2' around which an endless sanding belt B is adapted to travel; this belt B being composed of a suitable fabric having an abrasive substance on its inner surface.

The pulley 2' is mounted on a shaft 3 extending through adjustable bearing blocks 4—4' which in turn are supported upon a movable frame 5, slideable in suitable bearings on the frame A' and adapted to be adjusted thereon by means of a horizontally disposed threaded screw 6 mounted in a threaded bearing on the frame A'.

This screw 6 is provided with a hand wheel 7 on its outer end by means of which the screw 6 may be rotated so as to move the slideable plate 5 backward or forward on its mountings in the frame A' to move the pulley wheel 2' in such manner as to adjust the tension of the abrasive belt B. The bearings 4—4' are adjustable on the plate 5 so as to permit of the shaft 3 being alined to adjust the pulley 2' that the true travel of the belt B over the pulleys 2—2' will be insured. The pulley 2 is mounted on a drive shaft 3' revolvably mounted in fixed bearings on the frame A. The shaft 3' is rotated from any suitable source of power through a pulley 8 which is keyed on the 110

shaft. The pulleys 2—2' are designed to be spaced at a considerable distance apart to obtain a long span of the sanding or abrasive belt B, which span will be varied in 5 different machines to suit the length of the material to be handled.

Supported upon the frames A—A' and horizontally disposed therebetween is a vertically adjustable rectangular sub-frame 9. 10 A downwardly extending threaded bolt 10 on each corner of the sub-frame 9 is screwed into a revoluble nut 11 mounted between brackets on the frames A—A'.

A shaft 12 is mounted on each frame 15 A—A' and each shaft 12 carries a pair of worm gears which mesh with teeth formed on the outer perimeters of the nuts 11. The shafts 12 are rotated by means of hand-wheels 13, so as to revolve the nuts 11 in 20 their bearings to cause the bolts 10 to move up or down so as to raise or lower the sub-frame 9. The bolts 10 are hingedly connected to the sub-frame 9 to admit of a certain 25 rocking movement at that point which permits either end of the sub-frame being raised or lowered independent of the other.

Mounted on the upper face of the sub-frame 9 and transverse thereto, is a number of track rails 14 which extend the full width 30 thereof. These tracks may be extended some distance forward of the sub-frame 9, as shown in Fig. 1.

A movable carriage 17 provided with rollers 18 is mounted on the track 14 and is designed to be moved backward and forward laterally across the sub-frame 9 under the upper strand of the belt B. This carriage 17 carries track rails 19 extending longitudinally thereon, on which a table 20, having 35 rollers 21, is mounted and adapted to be moved backward and forward, parallel with the belt B. This table 20 may be operated by means of a hand-wheel 22 which rotates a hollow shaft or sleeve 23, mounted on the carriage 17, on which a pair of drums 24 is securely mounted; a pair of cables 25—25' wound on the drums 24 having their terminals extending in opposite directions and attached to the ends of the table 20 in such 40 manner that as the drums 24 revolve one cable will be wound on its drum while the other cable is unwound, thus causing the table 20 to move along the carriage 17.

From the foregoing it will be seen that the 55 table 20 may be moved into any position desired beneath the belt B, longitudinal adjustment being obtained by operating the hand-wheel 22, lateral adjustment by moving the carriage 17 on the sub-frame 9, and the horizontal plane of the table 20 being 60 adjusted by the hand wheels 13 by which the sub-frame 9 is raised or lowered. The latter adjustment permits of the distance separating the table 20 from the upper strand of 65 the belt B being regulated, as desired.

Means are provided by which the table 20 may operate mechanically, that is, driven by power.

The essence of the present invention resides in the mechanism for moving the 70 frame 17 and the table 20 on their respective track-rails so as to convey a panel carried by the table 20 lengthwise of the abrasive belt B and transverse thereof, or in a diagonal direction in relation to the belt, by operating the frame and table in unison. The mechanism for moving the table 20 comprises a pair of drums 24, having oppositely wound cables 25 and 25' thereon, the ends of 75 which are connected to the opposite ends of 80 the table, as shown in Fig. 1; the cables 25 and 25' being so wound on the drums 24 that when the latter is rotated in either direction, as will be later described, one of the cables 85 will wind on the drum to move the table 20 in one direction, while the other cable will unwind from the drum.

The drums 24 are rigidly mounted on a tubular shaft 23, journaled in suitable bearings on the underside of the table 20. Extending into the tubular shaft 23 from the rear side of the machine is a square shaft 23' which permits of a telescoping action of the shafts 23 and 23', and at the same time causes both shafts to rotate in unison when 95 one or the other is revolved.

The outer end of the shaft 23' carries a shiftable clutch member 26, which is slidable lengthwise on the shaft 23 and mounted to rotate thereon. The clutch member 26 is 100 normally held in engagement with a corresponding clutch member 27 by means of a spring 28 wound on the shaft 25 and bearing between a collar on the shaft 23' and the clutch member 26. The clutch member 27 is rigidly attached to or formed integral with a pinion 29, carried by a short-shaft journaled in a bearing 30 and having a gear 31 on its opposite end. The gear 31 meshes with a pinion 32 on a shaft 33, revolvably 105 mounted in suitable bearings.

Keyed on the shaft 33 to rotate therewith is a pulley wheel 34, and loosely mounted on the shaft 33 on each side of the pulley wheel 34 are idler pulley wheels 35 and 36. 115

Two continuous belts 37 and 38, the latter being a cross belt, are provided and are adapted to be shifted so that either of the belts may be positioned on the central pulley wheel 34, while the other belt will be on a loose pulley wheel 35, or 36; or both belts positioned intermediate the central pulley wheels 35 and 36 so as to neutralize their action on the central pulley wheel 34 and render the latter stationary.

The belts 37 and 38 lead to and pass around pulley wheels 39 and 40 on the drive shaft 3'. By shifting the belts 37 and 38 to or from the central pulley wheel 34, the direction of rotation of the latter may be changed as oc. 130

casion may require, so as to rotate the drum 24 in either direction when the clutch members 26 and 27 are in engagement with each other.

5 Means are provided for automatically shifting the belts 37 and 38 when the table 20 has reached an adjustable predetermined point in its travel in either direction so as to automatically reverse the direction of travel 10 of the table. This means consists of a slide- 15 able bar 41 mounted in suitable guides and having an upwardly extending standard 42 formed with an eye through which the upper run of the belt 37 passes, and also carrying a hanger 43 formed with an eye through which the lower leaf of the cross belt 38 passes. This bar 41 is adapted to be moved longitudinally by means of a revolu- 20 ble cylinder 44 disposed adjacent to the bar 41 and having a spiral groove 45 formed in its periphery into which a pin 46 on the bar 41 extends.

The drum 44 is rigidly mounted on a shaft 47, journaled in suitable bearings, and connected at one end to a square shaft 48 extending into and adapted to telescope with a shaft 49 supported in suitable bearings on the frame 19; the shafts 48 and 49 being movable longitudinally in relation with each 30 other and adapted to rotate in unison.

The shaft 49 carries a pinion 50 thereon which meshes with a gear 51 carried by the frame 17, which in turn meshes with a horizontal toothed rack 52 mounted on a reciprocating bar 53 extending longitudinally of the frame 17 and slidably supported in suitable bearings at each end of the frame 17.

Mounted on the rod 53 opposite the ends of the table 20 are adjustable stops 54, the 40 construction of which is particularly shown in Fig. 14. Each of the stops 54 consists of a split externally threaded conical sleeve 55, to which the stop 54 is attached, slidable on the rod 53, having a nut 56 screwed thereon 45 and contacting with a collar 56' adapted to contract the split sleeve 55 and clamp it in any desired position on the rod 53. The stops 54 extend upwardly into the path of travel of the ends of the table 20 in such 50 manner that when the table strikes a stop 54 the rod 53 will be moved lengthwise so as to cause the rack 52 to move therewith and thereby rotate the shafts 49-48 and 47, through the gear 51 and pinion 50, and there- 55 by rotate the drum 44 and cause the spiral groove 45 to act on the pin 46 to move the bar 41 lengthwise and thereby shift the belts 37 and 38, to change the direction of rotation of the drum 24 and accordingly reverse 60 the direction of travel of the table 20. From the foregoing it will be seen that the table 20 may be caused to travel back and forth at variable distances according to the location 65 of the stops 54, by the power-driven and automatic reversing mechanism just described.

As a means for stopping the movement of the table 20 and retaining it in a stationary position without cutting out the pulley wheel 34 and stopping the mechanism controlled thereby, a clutch shifting device is provided. 70 This device consists of a cam segment 57 on a square shaft 58 telescoping with a sleeve 59 on the frame 17; the cam disk 57 having a raised portion 60 arranged to be moved into engagement with a shoulder 61 of a ring 75 62, surrounding the clutch member 26.

The sleeve 59 is provided with a hand-wheel 63 on its outer end by the manipulation of which the clutch member 26 may be thrown in and out of engagement with the 80 clutch member 27, as may be desired, and thereby throw the drum 24 in or out of operative connection with the pulley wheel 34.

A hand-wheel 22 is mounted on the shaft 23 at the front of the machine to permit of 85 the manual reciprocation of the table 20, as occasion demands, and a hand-wheel 64 is mounted on the shaft 49 to permit of the manual operation of the belt shifting device 90 so that the belts 37 and 38 may be moved in or out of respective engagement with the pulley wheel 34 and into a neutral position independent of the table controlled mechanism.

The frame 17 is designed to be moved in a 95 direction at right angles to the direction of travel of the table 20, either continuously or intermittently, at strokes of travel of any predetermined length within the scope of travel of the frame. The reciprocation of 100 the frame 17 is accomplished by means of a worm-shaft 65, having right and left-hand spiral grooves *f* and *g* formed thereon; the shaft 65 being disposed transversely beneath the frame 17 and supported at its ends in 105 suitable bearings.

The connection between the frame 17 and the shaft 65 consists of a sleeve 66 slidably mounted on the shaft 65 and pivoted centrally on its horizontal axis to hangers 67 depending from the rear longitudinal side member of the frame 17. The sleeve 66 is recessed at its ends to receive annular disks or rings 68 and 69 which surround the shaft 65 and are connected thereto by means of inwardly extending teeth *h* and *i* which are formed on the rings 68 and 69, respectively, and extend into the spiral grooves *f* and *g*. The rings 68 and 69 are held in place in the recesses in the sleeve 66 by means of caps 70 115 which are screwed on the ends of the sleeve 66, as particularly shown in Fig. 3.

Interposed between the sides of the rings 68 and 69 and the adjacent sides of the sleeve 66 and caps 70, are anti-friction end-thrust 120 bearings 71. The outer peripheries of the rings 68 and 69 are formed with V-shaped teeth 72, and pivoted at 73 in a longitudinal slot on the underside of the sleeve 66 is a 125 rocker arm 74, the outer ends of which are 130

formed with teeth 75 and 75', adapted to extend between the teeth 72 on the rings 68 and 69. The rocker arm 74 is designed to be rocked so that when the tooth 75 is engaged with the teeth 72 on the ring 69, the tooth 75' will be disposed out of engagement with the teeth on the ring 68, as shown in Fig. 3. A detent spring 76 of any suitable construction is secured to the rocker arm 74 and operates to maintain the latter in either of its tilted positions.

Projecting downwardly from the arm 74 at its center is a finger 77 which extends between a pair of parallel rods 78 disposed beneath the shaft 65. Adjustably mounted on the rods 78 are spring-pressed bumpers 79 which extend in the path of travel of the finger 77 as the latter is moved backward and forward with the frame 17, as will be later described, and operate to rock the rocker arm 74 to throw it out of engagement with one of the rings 68 and 69 and into engagement with the other ring. The shaft 65 is designed to be rotated continuously in one direction from the shaft 33, irrespective of the direction of rotation of the latter. For this purpose the transmission mechanism, particularly shown in Figs. 8 and 9, is provided. This transmission mechanism is constructed as follows, reference being had to Fig. 8: Loosely mounted on a reduced portion of the shaft 65 is a sleeve 80, on which a pair of spaced ratchet wheels 81 and 82 is mounted. Formed on the ratchet wheel 81 is a ratchet clutch member 83 adapted to be engaged by a corresponding shiftable clutch member 84, splined on the shaft 65 and normally held in engagement with the clutch member 83 by means of a spring 85. Loosely mounted on the sleeve 80, between the ratchet wheels 81 and 82, is a spur gear 86 and a sprocket wheel 87, and mounted on the outer faces of the spur gear and sprocket wheel are pawls 88 and 89, which normally engage the teeth of the ratchet wheels 81 and 82. Meshing with the spur gear 86 and the pinion 29 is a series of intermeshing transmission gears 90-91-92 and 93, mounted in suitable bearings. Formed on the gear 91 is a sprocket wheel 94, around which a sprocket chain 95, leading around the sprocket wheel 87 is rove. When the pinion 29 is rotated in one direction, the spur gear 86 and sprocket wheel 87 will be correspondingly reversed. The pawls 88 and 89, however, are so arranged that when the spur gear 86 is rotated in the direction of the arrow *j* in Fig. 8, the shaft 65 will be rotated in the corresponding direction, and when the sprocket wheel 87 is rotated in the direction opposite the arrow *j*, the shaft 65 will continue to rotate in the same direction. The shaft 65 will therefore be rotated continuously in one direction from the shaft 33, during the time the clutch members 83 and 84 are in engagement with

each other. When the shaft 65 is rotated, the rings 68 and 69 will be revolved therewith by reason of their engagement with the spiral grooves *f* and *g*. By locking either of the rings 68 or 69 against rotation, which is accomplished by interposing a tooth 75 or 75' on the arm 74 between adjacent teeth 72 on a ring 68 or 69, the sleeve 66 will be caused to travel longitudinally of the shaft 65 by the screw action of the spiral grooves, thereby shifting the frame 17 laterally. When the frame 17 has reached the desired limit of its travel in either direction, the finger 77 strikes a bumper 79 and is rocked thereby so as to shift the rocker arm 74 and throw the tooth 75 or 75' thereon out of engagement with one of the rings 68 or 69, and throw the other tooth into engagement with the other ring, thereby locking the latter against rotation and causing reverse movement of the frame 17. In this manner constant reciprocating movement of the frame 17 is accomplished; the length of travel being governed by the location of the adjustable bumpers 79.

Means are provided for automatically stopping the movement of the frame 17 at intervals so as to give it an intermittent movement with a sufficient pause between each movement to allow the table 20 to traverse the length of its longitudinal movement in one direction. This means consists of a pivoted segment 96, having a cam face 97 adapted to travel in and out of engagement with a pin 98 secured to an arm 99, slidably supported upon the rods 78 and adapted to engage with the clutch member 84.

A downwardly extending arm 100 on the segment 96 is attached to a connecting rod 101 by means of a link 102. The connecting rod 101 extends horizontally beneath the frame 17 and is connected at its outer end to an arm 103, mounted on the rock-shaft 48. The segment 96, cam 97, rod 101 and link 102 are so arranged in relation to each other and to the shaft 48 that when the latter is in its normal stationary position the cam 97 will bear against the rod 78 and thereby retain the clutch member 84 out of engagement with the clutch member 83, thus causing the frame 17 to remain stationary. Normally the frame 17 is designed to remain stationary during the major length of travel of the table 20, and to move a short distance during the shifting of the belts 37 and 38. The shifting of the frame 17 at this time is accomplished by the rocking of the shaft 48, through the action of the table 20 on the stop-pin 54, as before described; the rocking of the shaft 48 acting to operate the segment 96 and move the cam 97 out of engagement with the pin 98 so as to allow the spring 85 to throw the clutch member 84 into engage-

ment with the clutch member 83, thereby causing the shaft 65 to be momentarily rotated. The release of the pin 98 from the cam 97 is effected intermediate the stroke 5 of the rock-shaft 48, so that when the latter completes its stroke the cam 97 will again be thrown into engagement with the pin 98 so as to normally hold the clutch member 84 out of engagement with the clutch member 83. The table 20 will thus move practically the length of the stroke, while the frame 17 is stationary, and when the table 20 nears the end of its stroke will act to shift the belts 37 and 38 to reverse its direction of movement, and at the same time 10 operate the clutch member 84 to cause the rotation of the shaft 65, and thereby effect a short movement of the frame 17; the movement of the frame 17 taking place during the shifting of the belts 37 and 38. This movement of the frame 17 is such as to move the panel carried by the table 20 laterally of the belt B in overlapping steps; the table 20 carrying the panel longitudinally 15 beneath the sanding point of the belt B during the interval between the step by step movements of the frame 17.

A rod 104 connects with the cam segment 96, and leading to the front of the machine 30 is provided with a hand-hold 105, by means of which the segment 96 can be manually rotated in opposition to a spring 96', when it is desired to maintain the clutch members 83 and 84 in engagement with each other, 35 independent of the cam 97. This is done when it is desired to cause the frame 17 to move simultaneous with the reciprocation of the table 20, so as to move the panel in diagonal relation to the belt B. The frame 40 17 will then move constantly from one side of the machine to the other and will be automatically reversed at the end of each stroke by the operation of the arm 74, as before described.

45 A hand-wheel may be provided on the shaft 65, by which the latter can be manually rotated when it is desired to shift the frame 17 independent of the driving mechanism.

50 When it is desired to cause the frame 17 to remain stationary during a number of reciprocations of the table 20, the clutch member 84 is held out of engagement with the clutch member 83 by means of a rod 98^b, 55 connected to the arm 99 and leading to the front of the machine; the rod 98^b being secured against movement by a catch 98^a when the clutch member 84 is out, or the rod may be manually held against movement to temporarily retain the clutch members 83 and 84 out of engagement.

55 Clamped on the upper end of a standard 106 is a horizontally disposed arm or bracket 107 which extends transversely 60 across the machine and terminates above the

belt B midway between the pulleys 2-2¹, in a vertically disposed tubular member or bushing 108. Mounted in the bushing 108 is a cylindrical casing 109 which has rack teeth formed on its side adapted to be engaged by gear teeth on a segment 110. The segment 110 is pivoted at 111 and has a lever handle connected thereto by means of which the segment may be rocked on its bearing to adjust the position of the casing 70 109 in the bushing 108. A thumb screw 112 on the segment lever extends through a slot on a bracket formed on the bushing 108 and is provided for the purpose of clamping the segment lever in a fixed position. 75

80 Mounted in the casing 109 is a plunger 113 on which is secured a stem 114 which extends upward through the top of the casing 109 and is guided therein. A spring 115, wound on the stem 114 between the top 85 of the plunger 113 and the end of the casing 109, normally retains the plunger in its lowermost position, and forms a cushion against upward pressure on the plunger 113.

85 A cross-head or bracket 116 is rigidly mounted on the lower end of the plunger 113 through which upwardly extending threaded studs 117 on a shoe 118 extend; wing nuts 119 being screwed on the upper ends of the studs to clamp the shoe 118 90 against a knob formed on the underside of the cross-head 113. The shoe 118 normally contacts the upper surface of the belt B when the casing 107 is in its intermediate position. 95

100 In operation, a panel or board 120 to be sanded is placed on the table 20 beneath the abrasive belt B and the level of the table is adjusted by the hand wheels 13 and their connections, to suit the thickness of the material to be worked. The frame 17 and the table 20 are then moved to the desired position in relation to the belt B and the shoe 118. The driving pulley 2 being then set in motion and the shoe 118 lowered upon the belt B, the latter is thrown into contact with the panel on the table 20 and is drawn thereacross by the rotation of the driving pulley 2. 105

110 It is obvious that the area of working surface of the belt B will be that of the shoe 118, so that in handling a panel of considerable size it will be necessary to shift from side to side and longitudinally, which is accomplished by operating the carriage 17 and the table 20, as before described, to bring the entire surface of the panel on the latter under the shoe 118. 115

120 A valuable feature of this machine is its adaptation for sanding thin veneers and finished panels, and that in subjecting the panel to the action of the abrasive belt B, the edges and corners of the panel will not be rounded off, for the reason that the belt B slopes downward in passing under and 125 130

away from the shoe 118, thereby confining the sanding action of the belt to the flat surface of the shoe 118. This feature is important inasmuch as the rounding of the edges and corners of veneered panels and the like is objectionable.

Having thus described my invention, what I claim and desire to secure by Letters Patent, is:

- 10 1. In a panel sanding machine, the combination of a movable frame, a table mounted to travel longitudinally on said frame at right angles to the direction of travel of the latter, means for automatically moving the table back and forth on the frame at predetermined lengths of travel, and means controlled by the movement of said table for shifting the frame including a normally inoperative clutch which is rendered momentarily operative by the table at the ends of the movements of the latter.
- 15 2. In a sanding machine, a stationary frame, a movable frame thereon, a worm-shaft, means for imparting movement to said frame by the rotation of the worm-shaft, a table mounted to travel longitudinally of the movable frame, a drum having oppositely wound cables thereon connected with the table, means for rotating said drum in alternate directions controlled by said table, and means for driving the worm-shaft from the drum rotating mechanism by which the worm-shaft will be rotated in one direction only.
- 20 3. In a panel sanding machine, a movable frame, a worm-shaft, means by which the rotation of the worm-shaft in one direction will impart reciprocal movement to the frame, a table mounted to travel longitudinally on the frame, a shaft, a drum on said shaft, oppositely wound cables on said drum attached to the opposite ends of the table, a rock-shaft, means for actuating the rock-shaft by the movement of the table as the latter nears the ends of its stroke, means controlled by the rock-shaft for alternately rotating the shaft and drum thereon in opposite directions, means for rotating the worm-shaft in one direction connecting with the drum-shaft, and means controlled by the table for throwing the worm-shaft in and out of operative connection with the drum-shaft.
- 25 4. In a sanding machine, in combination, with a carrier, a table thereon, and sanding means arranged over the table, constantly rotated means to move the carriage, a shiftable device, means whereby said device is shifted by and upon the table reaching its extremes of movement, and means normally disconnected from the constantly rotated means and moved into connection therewith by said device to thereby effect operation of the carriage.
- 30 5. In a sanding machine, in combination,

with a carriage, a table thereon and sanding means coöperating with the table, means to move the carriage, means whereby said moving means may be reversed, means to reciprocate the table on the carriage, and means actuated by the carriage upon reaching its extremes of movement to effect automatic operation of the reversing means.

6. In a sanding machine, in combination with a sanding means, a carriage and a table on the carriage, means to reciprocate the table, means to move the carriage including a driving element, a driver, a normally inoperative clutch between the driver and driving element, a rock shaft, means whereby the table upon the ends of its strokes will actuate the rock shaft, and means connected to the rock shaft and said clutch whereby upon movement of the rock shaft said clutch will be rendered operative to drive said driving element and thereby the carriage.

7. In a sanding machine, in combination with a sanding means, a carriage and a table on the carriage, means to reciprocate the table, means to move the carriage including a driving element, a driver, a normally inoperative clutch between the driver and driving element, a rock shaft, means whereby the table upon the ends of its strokes will actuate the rock shaft, a pivoted cam normally acting to hold the clutch inoperative, and a connection between the rock shaft and said cam whereby upon movement of the rock shaft said cam will be actuated to allow the clutch to couple the driver and driving element to thereby actuate the carriage.

8. In a panel sanding machine, the combination with an abrasive belt, of a panel-carrying table, means for moving the table lengthwise of the belt, separate means for moving the table transverse of the belt adapted to move continuously or step by step, and means for automatically reversing the direction of movement of the table both in transverse and longitudinal relation to the belt.

9. In a panel sanding machine, the combination with an abrasive belt, of a panel-carrying table, means for moving the table lengthwise of the belt, separate means for moving the table transverse of the belt adapted to move continuously or step by step, means for automatically reversing the direction of movement of the table both in transverse and longitudinal relation to the belt, and means for adjusting the length of travel of the table in relation to the belt.

10. In a sanding machine, a frame, a sanding means, a carriage on the frame movable laterally thereof, a table on the carriage movable longitudinally thereof, a shaft, means actuated by the shaft for moving the table, a second shaft, a slidable rod having stops thereon for engagement with the table,

- means whereby sliding of the rod will actuate the second shaft, reversible driving means, means connected to the driving means and to the second shaft whereby actuation of the latter will effect reversal of movement of the driving means, means actuated by the driving means to operate the first named shaft, a third shaft, reversible means between the third shaft and carriage, whereby the direction of travel of the carriage may be reversed, means for continuously actuating the third shaft from the driving means, and means operated by the carriage for actuating said reversible means of the third shaft.
11. In a sanding machine, a frame, a sanding means, a carriage on the frame movable laterally thereof, a table on the carriage movable longitudinally thereof, a shaft, means actuated by the shaft for moving the table, a second shaft, a slidable rod having stops thereon for engagement with the table, means whereby sliding of the rod will actuate the second shaft, reversible driving means, means connected to the driving means and to the second shaft whereby actuation of the latter will effect reversal of movement of the driving means, means actuated by the driving means to operate the first named shaft, a third shaft, reversible means between the third shaft and carriage, whereby the direction of travel of the carriage may be reversed, means for continuously actuating the third shaft from the driving means, and means operated by the carriage for actuating said reversible means of the third shaft.
12. In a sanding machine, a movable carriage, a table movable on the carriage at right angles to the direction of travel of the carriage, a sanding belt traveling longitudinally of the table and thereover, means to reciprocate the table longitudinally of the belt, constantly rotated driving means and means to periodically engage said driving means to move the carriage laterally of the belt step by step so as to allow the table to travel throughout a complete movement thereof during the periods lapsing between the movements of the carriage.
13. In a sanding machine, sanding means, work supporting means, means to reciprocate the work supporting means longitudinally of the sanding means, means to move the carriage laterally of the sanding means step by step so as to allow the work supporting means to travel throughout a complete movement during the periods lapsing between the lateral movements of the work supporting means and means whereby said carriage moving means may be operated to provide continuous movement of the carriage.
14. In a sanding machine, sanding means, a carriage, a table on the carriage, the carriage and table being relatively movable at right angles to each other, a shaft having right and left-hand spiral grooves, a member connected to the carriage and slidable on said shaft, means for connecting said member to either the right or left-hand groove of said shaft, means to actuate said connecting means, stops for operating said actuating means upon completion of predetermined lengths of movement of the carriage, and means to move the table.
15. In a sanding machine, sanding means, a carriage, a table on the carriage, the carriage and table being relatively movable at right angles to each other, a shaft having right and left-hand spiral grooves, a member connected to the carriage and slidable on said shaft, a pair of independent devices for connecting said member to the respective right and left-hand grooves of said shaft, a rockable device connected to each of said devices whereby when one is moved to operative position the other will be simultaneously operated to inoperative position, stops for engagement with opposite sides of said rockable device to actuate same, and means to move the table.
16. In a sanding machine, a movable carriage, a table movable on the carriage and at right angles to the path of movement of the carriage, driving means, means connected to the driving means and to the table for actuating the latter, means actuated by the table movements to reverse the direction of travel of the table, means actuated by the driving means to operate the carriage, and means actuated by the carriage movements to reverse the direction of travel of the carriage.
17. In a sanding machine, a movable carriage, a table movable on the carriage and at right angles to the path of movement of the carriage, means for actuating the table, and means also connected to said actuating means for intermittently operating the carriage and for selectively and manually enabling the last named means to continuously operate the carriage.
18. In a sanding machine, a movable carriage, a table movable on the carriage and at right angles to the path of movement of the carriage, means for actuating the table, means for actuating the carriage, means for reversing the carriage, and means actuated by the table upon reaching the end of travel thereof for effecting momentary actuation of the carriage actuating means whereby to move the carriage in step by step order.
19. In a sanding machine, a movable carriage, a table movable on the carriage and at right angles to the path of movement of the carriage, means to actuate the table, means to reverse the movement of the table, a constantly rotated driver, normally quies-

cent driving means for the carriage for advancing same, means for moving the carriage driving means into engagement with the driver, and means actuated by the table 5 upon the latter reaching an end of its travel for operating said means which renders the carriage driving means operative.

20. In a sanding machine, a movable carriage, a table movable on the carriage and 10 at right angles to the path of movement of the carriage, reversible means to actuate the table, means actuated by the table upon the latter reaching the ends of its movements to actuate said reversible means, reversible means for operating the carriage, and means actuated by the carriage upon the latter reaching the ends of its movements to actuate said last named reversible means.

21. In a sanding machine, a movable carriage, a table movable on the carriage and at 20 right angles to the path of movement of the carriage, reversible means actuated by the table to reverse the movement thereof, reversible means for actuating the carriage, 25 means whereby the table actuating means periodically operates the carriage, and means for reversing the direction of travel of the carriage upon the same reaching its limits of movement.

30. 22. In a sanding machine, in combination, with a sanding means, and a table co-operating therewith, means to move the table transversely of the sanding means at

intervals or continuously, and means to effect movement of the table longitudinally 35 of the sanding means throughout the said periodic or continuous transverse movement of the table.

23. In a sanding machine, in combination, with sanding means, a table co-operating 40 therewith, and a carriage on which the table is mounted, driving means for the table, reversing means for the table driving means, normally quiescent means to actuate the carriage, and a unitary means actuated by the 45 table movements to simultaneously operate said reversing means of the table and to render said carriage actuating means operative.

24. In a sanding machine, in combination, 50 with sanding means, a table co-operating therewith, and a carriage on which the table is mounted, driving means for the table, reversing means for the table driving means, means to operate the carriage, and means 55 actuated by the table movements to both actuate said reversing means and to periodically and simultaneously actuate the carriage operating means.

In testimony whereof I have hereunto set 60 my hand in the presence of two subscribing witnesses.

JOHN W. KROEZE.

Witnesses:

JOHN H. HERRING,
